THREAD ANVIL

Carl Russell and Hans R. Kiel, Downey, Calif.

Application March 21, 1946, Serial No. 656,083

1 Claim. (Cl. 33—167)

1

This invention relates to a screw thread anvil or gauge which is adapted to be used in measuring the pitch line of various threads.

An object of the invention is to provide a device which when used in conjunction with a micrometer caliper will determine the exact pitch of the thread being measured.

Another object of the invention is to provide a device that is simple in construction, efficient in operation, reliable in use and economical to manufacture.

With the above and other objects and advantages in view the invention consists of the novel details of construction, arrangement and combination of parts more fully hereinafter described, claimed and illustrated in the accompanying drawing in which:

Figure 1 is a side view of an embodiment of the invention;

Figure 2 is a plan view thereof;

Figure 3 shows the device in use with a tap to be gauged and a micrometer caliper and

Figure 4 is a sectional view on the line 4—4 of Figure 3;

Referring more in detail to the drawing the reference numeral 10 indicates the thread engaging anvil which is triangular in shape having the nearly sharp or slightly blunt edge 12, the edge 14 increasing in width over the edge 12, and the edge 16 increasing in width over the edge 14. The anvil 10 being of triangular shape comprises three faces. Face 15 extending from edge 16 to edge 14, face 17 extending from edge 14 to edge 12 and face 19 extending from edge 12 to edge 16.

The anvil 10 is provided with a bushing 17 shown in dotted lines in Figure 2 which is rotatably mounted on a shaft 18 which is fixed in the forked ends 20 of the handle 22. The bushing 17 is so mounted on the shaft that the anvil is free to rotate as desired.

When the anvil is to be used it is positioned as shown in Figure 3 with the anvil positioned between micrometer screw 24 and the tap 26, which is adapted to rest on the lower tip 28 of the micrometer 30.

The anvil is made of hardened metal and is ground to a perfect angle of 60° and the three edges previously mentioned are ground to prevent them from touching the root of the thread of the tap to be measured.

To use the anvil it is placed in the thread on top of the tap to be measured and the edge is used which does not touch the bottom of the thread. The spindle of the micrometer is placed

on the anvil and the pin of the micrometer on the bottom of the tap the micrometer and anvil is rolled to get the exact center and the micrometer reading is taken.

5 In using the anvil, the following formula is used:

Pitch or threads per inch	Constant		.10825 P Plus Single Depth
	P .10825	#2	
#1	#2	#3	
1	.10825		.75775
2	.05412		.37882
3	.03608		.25258
4	.02706		.18936
5	.02165		.15155
6	.01804		.12824
7	.01546		.10816
8	.01353		.09473
9	.01203		.08413
10	.01082		.07572
11	.00934		.06904
12	.00802		.06312
13	.00817		.05807
14	.00773		.05373
16	.00677		.04737
18	.00601		.04201
20	.00541		.03781
22	.00492		.03442
24	.00451		.03151
28	.00387		.02697

A or face 15=1"

B or face 16=A×.866

Formula:

$$B - \frac{.10825}{P} + \text{single depth} = C$$

35 C+major diameter=micrometer size.

Example.—Find mike size for 1 1/4" dia., 7 threads per inch, B=.380. Read down first column of table to 7, then across 3rd column to 40 .10816.

B or .380—.10816=.27184 or C

C or .27184"+major dia. 1.250"=1.52184 mike size

45 It is believed that the use of the anvil will be apparent to those skilled in the art and it is to be understood that changes in the details of construction and arrangement and combination of parts may be resorted to without departing from the spirit of the invention and the scope of the appended claim.

Having thus described the invention, what is claimed as new and desired to be secured by Letters Patent is:

55 A device of the character described for use with

a micrometer to measure the pitch line of the threads of various taps, comprising a triangular shaped body portion having three faces and two sides and one edge of the body portion at the faces thereof being nearly sharp, the second edge increasing in width over said first edge and the third edge increasing in width over the second edge and the edges are ground to prevent contact thereof with the root of the threads of the tap to be measured and the faces of said body portion are ground to a 60° angle with relation to the edges, a bushing mounted in said body portion extending through the body portion at right angles to the sides thereof, a shaft positioned in the bushing for rotatably mounting said body thereon and a flat handle having forked ends for mounting the ends of the shaft and the forked ends of the handle being parallel to the sides of the body portion.
